UNITED STATES PATENT OFFICE.

ARTHUR F. POOLE AND FRANK B. HALL, OF WHEELING, WEST VIRGINIA.

PARTY-LINE SIGNALING SYSTEM.

No. 810,346.

Specification of Letters Patent.

Patented Jan. 16, 1906.

Application filed October 13, 1902, Serial No. 127,114.

To all whom it may concern:

Be it known that we, ARTHUR F. POOLE and FRANK B. HALL, citizens of the United States, residing at Wheeling, in the county of Ohio and State of West Virginia, have invented a certain new and useful Improvement in Party-Line Signaling Systems, of which the following is a full, clear, concise, and exact description, reference being had to the accompanying drawings, forming a part of this specification.

Our invention relates to party-line signaling systems, such as are frequently employed for use in connection with selective party-line telephone systems.

We disclose herein a selective party-line telephone system employing two metallic lines, one of which may be looped in to form a series connection at all or any desired number of substations upon a party-line. The other of the two metallic lines is preferably provided with a parallel or bridge connection with each of the substations. In connection with this system we find it desirable to employ a ground return-circuit, which acts in conjunction with the loop or series metallic wire. Selective apparatus is desirably installed at each of the substations upon the party-line such that currents passing over a circuit formed by the series wire to any given substation and thence through the ground to the central station will build up the loop-line through that substation. This building up of the loop-line will be accomplished no matter in which direction the currents pass through the building-up circuit; but the selective apparatus located at each of the substations is further provided with other instrumentalities such that when the selective currents pass in what may be termed the "normal" direction only the building up of the line is accomplished, while when the currents pass in the opposite direction this line is not only built up, but a subscriber's signaling instrument, such as a telephone, is also thrown into bridge connection across the telephone-lines. Thus in order to build up the party-line and to connect any desired substation with the metallic line it is necessary to provide at the central station instrumentalities which are adapted to send a number of impulses over the building-up circuit corresponding to the number of substations located upon any party-line, any desired num-

ber of which current impulses may be reversed in direction, so as to connect in the telephone instruments at such substations as may be desired. In the selective apparatus employed the mechanism which builds up the loop-line also serves to disconnect the ground return-circuit, so that no further currents may flow through the setting-up circuit without first restoring the selective apparatus to its normal condition. This restoration is accomplished, preferably, by the flow of a current controlled from the central station over both limbs of the metallic line to which the substation apparatus has been connected in bridge during the building-up process. The actuation of the switches at substations is accomplished by the power stored in suitable mechanism upon the closure of circuit through actuating - electromagnets. The actuation of the switches is thus made to occur wholly upon the cessation of the flow of the current impulse through the electromagnets.

It is desirable that the control of the selective apparatus employed be from the central station, which necessitates the provision of apparatus at the central station capable of sending current impulses of either polarity over the series ground-return setting-up circuit. It is further necessary that the central-station apparatus be capable of causing a battery-current to flow over the two metallic limbs of the line to restore the selective apparatus. As is common to other telephone systems, the central-station equipment must also include cord connecting apparatus for connecting subscribers who desire conversation with each other and line-signaling apparatus by which the subscriber may notify central that he desires a connection. Our party-line telephone system also includes means whereby a subscriber may, when the party-line is not in use, connect his own instrument in bridge thereof in order to converse with the central operator or other subscribers. This feature requires the provision of means at the central station for sending current through certain electromagnetic devices of the selective apparatus which actuate the switching mechanism which controls the inclusion of the subscriber's telephone instruments in circuit.

Our present invention relates particularly to central-station equipment adapted espe-

cially for connection with our said party-line system and which central-station equipment is well adapted to render automatic many of the otherwise manually - controlled operations necessary in the proper working of our system.

Our invention will be best understood by reference to the accompanying drawings, in which—

10 Figure 1 is a diagrammatic view illustrating a preferred embodiment of the central-station equipment, and Fig. 2 is a diagrammatic view illustrating a party-line adapted for use in connection with the said central-station equipment.

In both figures like reference characters are used to designate similar parts.

It will be necessary for a complete understanding of our present invention to describe 20 in general the selective party-line and its associated devices which may be used in connection with the central - station equipment which is the subject of our present invention.

Referring more particularly to Fig. 2, it 25 will be seen that we have provided a metallic line *a*, whose continuity is normally broken at each of the substations through which said line passes. We also provide a second metallic line *b*, which is preferably continuous 30 through all the substations and to which it is connected in parallel. At each of the substations is provided an electromagnet 1, normally connected with ground *G*, the remaining terminal of which is desirably connected 35 in series through the electromagnet 2 with the contact 3, which normally makes connection with the switch 4 to the line-wire *a*. An electromagnet 5 is also provided, having a permanent connection with the line-wire *b*, 40 whose other terminal 6 is adapted to make contact with the switch 4 in its alternative position. Telephone or other signaling apparatus 7 is provided with a normal connection with the line *b*, the remaining connection 45 through the condenser 8 being normally open between the contact 9 and the switch 10, which is connected with the line-wire *a*. A terminal 11, normally in contact with the switch 4, is provided with a connection which 50 may be closed through the key 12 with the connection to the line-wire *b*. Contact 13 when engaged by the switch 4 closes the loop-circuit through the substation at which it is located. The metallic limbs of the line 55 are connected at the central station with a spring-jack in the usual manner, the line-wire *a* being connected with the tip-spring 14, while the line *b* is connected with jack-spring 15. A circuit is normally closed between the spring 15 and the ground *G* 60 through the line-drop 16 and the battery 17. The mechanism of the electromagnets 1 and 5 is operated by a current flowing through the corresponding electromagnets in either 65 direction, while a current in order to effect an

actuation of the mechanism connected with the electromagnet 2 must be of a certain polarity—that is to say, in one given direction. As previously stated, it should be remembered that Fig. 2 is merely a diagrammatic representation of the circuit arrangements and that the switches 4 and 10 are not directly actuated upon the energization of the electromagnets, but that these electromagnets control mechanism adapted to cause actuation of the switches only upon the cessation of the flow of the current through the electromagnets.

In general the operation of our system may be described as follows: A subscriber—say at 8c substation 201—desiring connection by the central operator with some other subscriber closes his key 12, thereupon closing a circuit, which may be traced as follows: from the *b* wire to the key 12, the contact 11, the switch 4, the contact 3, to electromagnet 2, to magnet 1, and to ground *G*. As will be hereinafter more fully described, there is provided at the central station a battery 17, one of whose terminals is grounded and the other of whose terminals is normally connected with the line-wire *b*. This battery is connected in such a direction that its current flowing through the electromagnet 2 will cause an actuation of the switch 10 on account of its polarization 95 and switch 4 will be actuated by the electromagnet 1, whereupon the circuit just traced from contact 11 to contact 3 will be broken and the contacts 6 and 13 connected with the switch 4. Thus the break in the loop-wire *a* is built up through the station 201, the ground connection *G* is removed, and a connection is established between the *a* wire, through the switch 4, the contact 6, and the electromagnet 5, with the line-wire *b*; also, on account of the 100 actuation of the switch 10 terminal 9 of the telephone instrument 7 will be connected with the line-wire *a*, thereby placing the telephone set in bridge across the metallic lines. In order that the remaining substations upon 105 a given party-line may have their ground connections thrown off and the series wire built up through the said stations, it is necessary that a number of impulses be sent from the central station through the line-wire *a* 110 and the successive substations and the ground return - circuit. Such an impulse, affecting the instruments at substations 202, may be traced from central stations as follows: from the line-wire *a* at the central station to the 115 switch 4 at substation 201, to contact 13 at the same substation, through the line-wire *a* to the switch 4 at substation 202, to contact 3, through electromagnet 2, through electromagnet 1, to the ground *G*, and thus to the 120 central station. These impulses will normally be sent in a direction such that the switches 10 will not be actuated. If the central operator desires to call a given substation upon a party-line, the impulses sent from 125 130

the central station between the *a* wire and ground must be all in a normal direction which will not actuate the switches 10, except that the impulse or impulses corresponding with the number or numbers of those substations which are to be connected with the line must be sent in a reverse direction in order to actuate the corresponding switches 10, thereby placing the desired telephone instruments in bridge of the metallic line. Upon the completion of the conversation between the subscribers it is necessary that battery-current be sent over the metallic limbs *a* and *b*, which will restore all the selective apparatus to its normal condition. This restoration is accomplished because, it will be remembered, the electromagnets 5 have previously been bridged across the metallic lines during the building-up process, and an energization of these electromagnets returns the switch 4 to its normal position, at the same time breaking the contact between switch 10 and contact 9. In our said other application we have described manually-operated central-station devices designed to accomplish the proper building up and restoration of the party-line, also means for selecting any desired station or stations for conversational purposes. Our present invention contemplates automatic central-station devices such that the building-up and restoring processes may be carried on without the direct attention of the central-station operator.

Our improved central-station equipment may perhaps be best described by tracing the various circuits employed in carrying out the various operations connected with the use of our system. Taking first the condition under which a subscriber—for instance, at substation 202—calls central, it will be remembered that the subscriber closes his switch 12, whereupon a circuit may be traced from the ground *G* at the substation through the electromagnets 1 and 2 and the contact 3 and switch 4 to contact 11; through switch 12, which the subscriber closed, to line-wire *b*, to sleeve-spring 15 of the spring-jack at the central station, to contact 18, to line-signal 16, to relay-spring 20, to contact 21, through battery 17, to ground *G*. The polarity of this battery 17 is such that current therefrom will actuate the various mechanism connected with electromagnet 2, to actuate the switch 10 at substation 202; through which the subscriber has closed circuit by means of his switch 12. Also the electromagnet 1 may or may not have been energized sufficiently to actuate the switch 4. However, the current is sufficient to actuate the line-signal 16, whereupon the target 23 is released to make contact with the terminal 24 of the relay-coil 25. Thus a local circuit is closed through the relay-coil 25 and the local battery 26, whereupon the armature 27 is attracted, breaking a momentary circuit

which has been established through the spring 20 and contact 21 and which, it will be remembered, was the current which actuated the subscriber's switch 10. Furthermore, the energization of the relay 25 causes a closure of the circuit between the spring 28 and contact 29 and between the spring 30 and the contact 31. It might be noted here that the armature 27 and its associated spring-contacts are controlled by the target 23. Starting at contact 31, a circuit may be traced as follows: through the conductor 32 to set-up relay 33, to electromagnet-coils 34 of the vibrator 35, to contact 36, through the mercury 37 to contact 38, through conductor 39 to spring 40 of the pole-changing switch 41, to negative pole of battery 42 from the positive pole of the battery 42, through conductor 43, to contact 44, to spring 45, to conductor 46, to spring 30, back to contact 31.

It may be desirable here to point out the essential features in the operation of the vibrator 35. It consists of a horseshoe-electromagnet 47, having coils 34, between the poles of which electromagnet is pivotally mounted the armature 48. Rotatably mounted with the armature 48 is an exhausted tube 49, containing a small quantity of mercury 37, into which tube are sealed the two contacts 36 and 38. The normal positions of the armature and mercury-tube are such that there is an electrical connection between the contacts 36 and 38 through the mercury 37. Upon the energization of the electromagnet the armature is turned sufficiently to break the circuit between the contacts 36 and 38. This of course breaks the circuit traced through the electromagnet-coils, which thereupon become deenergized and allow the armature to swing back into its normal position. The weight and inertia of the armature is such that the period of oscillation thereof is rather slow—for example, the vibrator may close and open its circuit once in a second. Thus upon the attraction of the armature 27 an electric circuit may be traced through the set-up relay 33 and the vibrator 35, which vibrator will at once begin to open and close the said electric circuit. This of course will cause the attraction of the armature 50 of the set-up relay 33 a number of times corresponding with the number of oscillations of the vibrator-armature. This armature 50 controls a circuit which may be traced as follows: from the armature 50 to contact 51, to lamp-relay 52, to ground *G* at the central station, to ground *G* at the first substation 201, through electromagnets 1 and 2 to contact 3, to switch 4, to line-wire *a*, to tip-spring 14, to tip-contact 53, to relay contact-switch 28, to contact 29, to spring 54, to contact 55, to spring 45, to contact 44, through conductor 43 to positive battery 42, to contact 56, to spring 40, through conductor 57, to armature 50. This upon the

closure of a subscriber's switch 12 the vibrator 35 is set in operation, which in turn sets in vibration the armature 50, which in turn controls a series of electrical impulses sent 5 out between the line-wire *a* and ground. Since the line-wire *a* is normally broken at each of the substations, the first impulse can actuate the selective mechanism only at the first substation upon the line; but the actuation 10 of the apparatus at this substation builds up the series line *a* to the second substation, whereupon each succeeding impulse sent between the line-wire *a* and ground builds up the break in the line *a* at a corresponding substation. At the same time that 15 the break in the loop at any one substation is connected the ground connection at that substation is broken. Thus each successive impulse has but one path of travel through 20 but one substation. The selective apparatus at the substations is so constructed that a circuit change—that is, the actuation of the switch 4 itself—occurs only upon the cessation of the current-flow, except that the electro- 25 magnet 2 operates switch 10, controlled thereby, immediately upon the flow of current of proper polarity therethrough. It is immaterial what the form of mechanical arrangement of the switching mechanism is, so long as 30 the switching occurs upon the cessation of current-flow. Thus upon a sufficient number of vibrations of the vibrator all the loops in the broken line will be built up and all the ground connections thrown off. It will be remembered that the subscriber who set in motion the 35 trend of operations thus described has closed his switch 10 to bridge his instruments across the metallic limbs of the line. It will be seen that immediately after the closure of his 40 switch 12, the line and selective apparatus being in their normal condition, instrumentalities at the central station are set in operation to at once automatically build up the line and throw off the ground connections, the 45 calling subscriber 202 being connected in bridge of the metallic line. The central-station operator receives the signal upon the drop of the target 23. It will be noticed that the electromagnet 52 controls, by means of its 50 armature 58, the following circuit through the signal-lamp 59: from positive pole of the battery 42 to contact 44, to switch-contact 45, to conductor 46, to the contact associated with the armature 58, through the armature 55 58 to the lamp 59, through the conductor 57 to the switch-contact 40, to contact 56, to the negative pole of the battery 42. The current through the electromagnet 52 is an intermittent one, corresponding in its period 60 with the setting-up current controlled by the relay 33. The circuit, furthermore, through the relay 52 can be traced only while there remains one or more ground connections at the substations upon the party-line. Thus 65 the lamp 59 is caused to flash intermittently

while the line-wire *a* is being built up, and after the completion of this building-up process the lamp 59 will become extinguished, as the circuit through relay 52 will be broken upon the ground connections at the substations being broken. Thus this lamp provides a signal for the operator by means of which she may ascertain whether or not the party-line has been completely built up. Therefore when the lamp has stopped flashing she may manually restore the drop-target 23, which breaks the local circuit through relay 25, thus preventing further actuation of the vibrator 35 and the relays controlled thereby, having first, however, plugged into 70 the jack, breaking the circuit between the springs 14 and 15 and their associated contacts. The usual operator's cord-circuit is provided between the answering-plug 60 and the calling-plug 61. A clearing-out relay 62 75 in series with the condenser is bridged across the cord-circuit, the operator's set 63 and ringing-generator 64 being provided, as usual. After plugging into the answering-jack the operator ascertains the number of the subscriber with whom the calling party desires 80 conversation and makes the connection in the usual way. The operator upon receiving a disconnect signal through her drop 62 must restore to its normal condition the party-line. 85 This, it will be remembered, is accomplished by sending a comparatively heavy battery-current across the metallic limbs of the line. Since the cord-circuit is connected with the lines *a* and *b*, the restoring-current is preferably connected with the line through the cord-strands. Thus the contacts 65 and 66, which, it will be seen, are connected with the terminals of the battery 42, may be brought 90 into bridge connection with the cord-circuit 95 by a manipulation of the key which operates springs 67 and 68, these springs being connected each with a strand of the cord-circuit. 100 A second operative condition is that in which a given subscriber upon a party-line is 105 to be called. Supposing that substation No. 3 on party-line 200 is to be called. In order to accomplish this, it will be necessary to send a number of impulses between the *a* wire and ground corresponding to the number of substations upon the party-line. The third of 110 these impulses must be in a reverse direction, so as to operate the switch 10 at substation 203. The operator inserts her calling-plug 61 between the jack-springs 14 and 15, inserts the selector-plug 69 in No. 3 of the selector-jacks 70. She then depresses a single key, spreading the springs 71 and 72 and 73 and 74. The depression of spring 74 breaks 115 a connection through the tip-strand with the answering-plug 60, while the raising of the spring 71 breaks the connection with the sleeve-strand from the plug 60. The movement of these springs also establishes other 120 circuits, which will be hereinafter traced. A 125 130

depression of the spring 72 causes a connection with contact 75, which may be traced therefrom to the set-up relay 33, to the vibrator-coils 34, to its contacts 36 and 38, to the 5 conductor 39, through spring 40 to contact 56, to negative battery 42, from plus battery through conductor 43 to contact 44, to spring 45, through conductor 46 to conductor 76, to spring 72. Thus an intermittent pulsating 10 current is set up through the agency of the vibrator, while the armature 50, controlled by set-up relay 33, causes intermittent pulsating currents to be sent from negative battery to ground G, while positive battery is connected to the *a* wire through the tip-strand of the cord-circuit. This circuit may be traced from the spring 71, connected with the tip-strand, to the contact 77, to conductor 76, which, it will be remembered, is connected directly 15 to the positive battery. As previously described, the flashing of the lamp 59 will indicate the progress of the building-up process.

It will be remembered that in order to connect the substation 203 across the metallic lines *a* and *b* it is necessary that the third of the setting-up impulses be in a reverse direction. The armature 78 of the pole-changing switch 79 controls the springs 40, 45, and 54 and is actuated by the energization of the 20 electromagnet 80. Therefore in order to reverse the direction of one of the setting-up impulses—for instance, the third—it will be necessary to cause the energization of the electromagnet 80, which of course, through 25 the pole-changing switch 79, will reverse the connection of the battery 42 with the setting-up circuit. To accomplish this proper reversal of the current, counting mechanism 81 is provided. It will be seen that the tip-springs of the selector-jacks 70 are connected each with a contact-button 82 of the counting device. A rotatably-mounted switch 83 is adapted to be stepped around so as to make contact successively with the buttons 30 82. The step-by-step operation of the switch-arm 83 is accomplished by means of a ratchet-wheel 84, actuated by a pawl 85, carried upon a lever 86, which is actuated upon the energization of the electromagnet 87. 35 The circuit for the electromagnet 87 may be traced as follows: Upon the manipulation of the spring 73 contact is made with the contact 88, from which circuit may be traced through the conductors 76 and 46 to the spring 45, to contact 44, to positive battery 42, from negative battery to contact 56, to spring 40, through conductor 39, to contact 38, through the mercury 37, to contact 36, to conductor 89, to electromagnet 87, through 40 conductor 90, to spring 73. It will be seen that this circuit is interrupted by the breaking of the circuit within the vibrator-tube, which, it will be remembered, has been set in operation. Thus as each setting-up impulse 45 is sent out over the line the electromagnet 87

will be energized to attract its armature mounted upon the lever 86, thereby withdrawing the pawl 85 back over one tooth of the ratchet-wheel 84. Upon the deenergization of the magnet 87 when the current is interrupted by the vibrator the counterweight 70 91 upon the lever 86 causes a reverse movement of the pawl 85, which moves the switch-arm 83 into contact with the succeeding button 82. Thus the first setting-up impulse 75 moves the switch 83 into contact with the second button, which is connected with the tip-spring of the second selector-jack. Similarly the second setting-up impulse moves the switch-arm 83 into contact with the third 80 button, which is connected with the tip-spring of the third selector-jack, into which, it will be remembered, the selector-plug 69 has been inserted, so that a connection is formed between the selector-plug 69 and the 85 switch-arm 83 immediately upon the cessation of the flow of the second setting-up impulse. Thus after the cessation of the second setting-up impulse a circuit may be traced as follows: from the switch-arm 83, 90 through the conductor 92, connected therewith, to the electromagnet 80, to positive battery 42, through conductor 93, to selector-plug 69, to the tip-spring of No. 3 selector-jack, to the No. 3 95 contact-button, back to the switch-arm 83. Thus a circuit is closed which energizes the electromagnet 80, thereupon actuating the pole-changing switch 79. Thus the succeeding actuation of the armature 50, controlling 100 the setting-up currents, will cause the setting-up current to flow between the *a* wire and ground in a reverse direction, which direction must be such as to cause the proper energization of the electromagnet 2 at substation 203 to actuate the polarized switch 10 to connect the subscriber's instruments in bridge of the metallic telephone-lines *a* and *b*. Upon the cessation of the flow of this reversed setting-up impulse the switch-arm 83 105 will move on to the fourth button, thereupon breaking circuit through the electromagnet 80, whereupon the retractile spring will cause the pole-changing switch to resume its normal condition. Thus the getting-up impulse 110 corresponding with the number of the subscriber to be called upon a party-line will be automatically reversed in direction without the immediate care and attention of the operator. As previously pointed out, the flashing of the lamp 59 will indicate that the line 115 is being built up, and when the flashing ceases the operator may release the springs 71 and 72 and 73 and 74, thereupon permitting conversation between the connected subscribers 120 through the cord-circuit. Any desired subscriber may be connected into circuit by the insertion of the selector-plug in the proper selector-jack. Upon receiving a disconnect-signal 125 the operator may restore the party- 130

line by the manipulation of the key connected with springs 67 and 68, as heretofore pointed out.

The counting mechanism 81 will have its switch-arm 83 stepped around a number of spaces corresponding with the number of energizations of the electromagnet 87. A clock-spring 94 is desirably provided, which upon the release of the pawl 85 and the detent-pawl 95 causes the ratchet-wheel and switch-arm to be swung back against the stop 96. An electromagnet 97 is provided for the purpose of actuating the armature-lever 98 to release the pawls 85 and 95. This restoration of the counting mechanism is accomplished by a circuit which may be traced from negative battery 42 through the conductor 93 to the tip of the plug 69, which when being removed from any one of the jacks 70 makes a momentary contact with the long jack-spring thereof, whereupon circuit may be traced through the said spring and the conductor 99 to the electromagnet 97, to positive battery 42. Thus this momentary current actuates the lever 98 to release the pawls and allow the ratchet-wheel and switch to return to their normal position. If for any reason the momentary current flowing through the restoring-electromagnet fails to properly restore the counting mechanism, the operator makes another restoring-circuit by a momentary contact between the selector-plug and the long spring of the selector-jack when she inserts the selector-plug into the jack—that is, the operator has what may be termed a "double" certainty of properly restoring the counting mechanism, once when she removes a selector-plug from the jack and again when she inserts a selector-plug in order to call another subscriber.

Each operator's position may be desirably provided with two or more plugs connected in parallel with the selector-plug 69, whereby, for instance, the insertion of two plugs within two of the selector-jacks 70 will cause a reversed setting-up impulse to be sent through two substations, whereupon the telephone instruments at these two substations will be connected in bridge of the telephone-lines. This is necessary in case a subscriber on any one party-line desires conversation with another subscriber on the same party-line. The calling subscriber will get central in the usual manner, whereupon the party-line will be automatically set up, as previously described. Upon making it known to the central operator that connection is desired with another subscriber upon the same party-line the operator first restores the selective apparatus on the party-line by a depression of the key controlling the springs 67 and 68 and thereafter places selector-plugs in the jacks corresponding with the two subscribers desiring conversation, whereupon the line is again set up, but with two setting-up im-

pulses properly reversed to connect in the two desired substations.

One of the above-described automatic setting-up equipments is desirably provided for each operator's position. Since such an operator's position may desirably be connected with a number of party-lines, it frequently happens that a subscriber may be calling at the same time another party-line is being set up. As heretofore pointed out, the setting-up impulses which are automatically caused to flow when the subscriber closes his switch 12 should all be in one direction, and this direction should be the normal one, so that none of the switches 10 at any of the substations will be actuated by the setting-up impulses sent out from the central station; but when an operator is calling a subscriber on a party-line at least one of the setting-up impulses should flow in the reverse direction in order to connect in the called subscriber. This reversal of current is effected by the pole-changing switch 41, due to the energization of the electromagnet 80. Since this actuation of the pole-changing switch reverses the battery connection with the circuits associated therewith, the natural result would be that a reverse current could be sent out over both the party-line on which the calling-substation was located and that on which the called substation was located. This of course would cause an improper building up of the calling party-line, the reverse current serving to connect in a substation which should have no connection across metallic lines *a* and *b*. To obviate this improper setting up of the calling-line which would result from the improper reversal of the setting-up current, we have provided the switch 54, which is normally in connection with the contact 55. The automatic setting-up current normally passes through this connection; but upon the energization of the coil 80 the pole-changing switch is actuated, and since the spring 54 is controlled by the same armature 78 this normal connection is broken, whereupon no setting-up impulse is sent over the calling-line at the time at which a reversed current is automatically sent over the called line. Thus while the calling-line misses one of the setting-up impulses, which would normally have been sent out over the same, all of the impulses which are sent out over this line are in the proper direction and no false actuation of the instrumentalities on the calling party-line is caused by the reversal of the battery connections necessary to the proper setting up of the called line.

In practice we find it desirable to mount the vibrator, counting mechanism, pole-changer, and the set-up and lamp relays all upon one base-board provided with terminal posts, from which may be run the conductors leading to the selector-jacks, the switching devices controlling the operation of the de-

5 vices mounted on the said base-board and the conductors through which impulses are sent. It will be seen that the invention provides automatic setting-up devices for use at a central station in connection with a great variety of party-line telephone systems.

10 While we have particularly described our invention as adapted for employment with a particular party-line system, it is not to be understood that the present invention is limited to application to this system alone.

15 Our invention provides means whereby a party-line is entirely set up and the calling subscriber properly connected therewith without any care or attention from the central-station operator whatever, it being merely necessary that the operator upon receiving a proper signal—such, for instance, as that given by the lamp 59—plug into the 20 proper answering-jack and thereafter communicate with the calling subscriber in exactly the same way as she would with a subscriber connected with a single metallic line.

25 While we have shown a manually-restored drop 16, it will be apparent to those skilled in the art that any self-restoring drop might be substituted therefor.

30 Particular advantages are gained by the use of our improved central-station equipment due to the feature which we may term the "instantaneous lockout." It will be seen that immediately upon one subscriber closing his switch 12 the drop-target 23 is released, thus closing a local circuit through the relay-coil 25, whereupon the armature 27 is attracted and the current from battery 17, flowing between contact 21 and spring 20, is interrupted. Since it is necessary for any other subscriber in order to bridge his telephone instruments across the *a* and *b* wires to obtain battery-current from the battery 17 through a connection between the contact 21 and switch 20, this second subscriber cannot connect in his instruments after this connection has been broken. Thus when the first calling subscriber breaks this connection upon depressing his switch 12 all the remaining substations on the same party-line are instantly and effectually locked out. It 45 might occasionally happen that a subscriber on a party-line would wish to obtain connection with the central station during the time at which the line was being set up from the central station. If the subscriber who thus wished to call central was located a considerable number of substations from the central station, it is possible that as the line was set up through the nearer substations a sufficient amount of current could pass through the restoring-electromagnets which were bridged between the *a* and *b* wires to allow a current to flow through the *b* wire sufficient to actuate the switching mechanism at the more remote station. The circuit then at this more 55 remote station at which a would-be calling

subscriber had closed his switch 12 would be from the ground through the electromagnets 1 and 2 to the contact 3, through the switch 4 to contact 11, and through the then closed switch 12 to the *b* wire. Thus a circuit would be established through which a current might flow to actuate the switch 4; but, it will be remembered, the normal setting-up impulses are in such a direction that the switch 10 at this more remote station would not be actuated. Hence the second subscriber's instruments would not be connected across the line. Our system presents another advantage over the central station arrangements heretofore used for selecting subscribers on a party-line 80 in the great simplicity of the means employed by which a central-station operator may select any desired substation. It is merely necessary that the operator place a selector-plug in the proper selecting-jack. This is a 85 great advance over those systems in which the operator must insert pins in a switch-dial or otherwise manipulate contact-points therein and then, for instance, actuate a spring-motor mechanism adapted to operate proper 90 switching or pole-changing mechanism. Such systems of the prior art, furthermore, require a number of operations by the central-station operator in properly restoring both the line mechanism and the central-station mechanism. 95 Our invention, it will be seen, provides for the complete restoration of the party-line by the manipulation of a single key on the operator's board, and the mere removal of the selector-plug from the selecting-jack restores the central-station mechanism to its 100 normal condition. Of course the cord-circuit plugs must be removed from their jacks, as in any other telephone system.

105 In the case of a calling-station located on a party-line our invention provides means whereby there is required of an operator only one operation in addition to those necessary in any simple telephone-exchange board, and in case the called station is located on a party-line only three additional operations will be required. In the first case the one additional operation consists in a manipulation of the restoring-key controlling the springs 67 and 68, and in the second case the additional operations consist, first, in placing the selector-plug in a proper selector-jack, second, in manipulating the key controlling the springs 71 and 72 and 73 and 74, and, third, in manipulating the restoring-key, as in the first case. 110 The only space required by the instrumentalities employed in our system in addition to that required in any exchange-board is the small space occupied by the restoring-keys and the setting-up keys, one of each for each 115 cord-circuit, and a bank of selector-jacks for each operator's position. The number of selector-jacks should be at least as great as the largest number of substations on any one party-line connected with that position. 120 125 130

While we have herein shown and particularly described one preferred embodiment of our invention, it will be apparent to those skilled in the art that many modifications 5 therein might be incorporated without departing from the spirit of our invention. We therefore do not wish to limit ourselves to the precise disclosure herein set forth; but,

Having described our invention, we claim 10 as new and desire to secure by Letters Patent—

1. In a selective party-line system, the combination with the central station, of lines running therefrom to a series of substations, 15 signaling apparatus at each of said substations normally disconnected from said lines, means at each substation absolutely controlled from the central station, and from the said substation, whereby the corresponding 20 signaling apparatus may be connected with said lines, and means whereby an actuation of said first means controlled from the corresponding substation, establishes a condition such that the substation control at the other 25 substations of the said first means is rendered ineffective, substantially as described.

2. In a selective party-line system, the combination with the central station of lines running therefrom to a series of substations, 30 signaling apparatus at each of said substations, normally disconnected from said party-lines, means primarily controlled from the central station, and secondarily controlled from each substation, whereby the corresponding 35 signaling apparatus may be connected with said lines and means whereby an actuation of said first means controlled from any one substation, establishes a condition such that the substation control at the other 40 substations of said first means is rendered ineffective, substantially as described.

3. In a selective party-line system, the combination with a central station, of lines running therefrom to a series of substations, 45 signaling apparatus at each of said substations normally operatively disconnected from said lines, means controlled from the central station whereby any of the signaling apparatus may be operatively connected with the 50 said lines, said means being subject to a secondary control from each substation, the control exercised from any one substation serving secondarily to govern the operative connection of the signaling apparatus at the 55 same substation with said lines, and means whereby an actuation of said first means due to the control exercised from any one substation establishes a condition such that the substation control at the other substations of the 60 said first means is rendered ineffective, substantially as described.

4. In a selective party-line system, the combination with a central station, of lines running therefrom to a series of substations, 65 signaling apparatus at each of said substations normally operatively disconnected from the said lines, means primarily controlled from the central station whereby the signaling apparatus at any substation may be operatively connected with the lines and secondarily controlled from each substation, the control exercised from any one substation serving secondarily to govern the operative connection of the signaling apparatus at the same substation with said lines, and means whereby an actuation of said first means due to the control exercised from the central station establishes a condition such that the substation control at the other substations of the said first means is rendered ineffective, substantially as described.

70

tions normally operatively disconnected from the said lines, means primarily controlled from the central station whereby the signaling apparatus at any substation may be operatively connected with the lines and secondarily controlled from each substation, the control exercised from any one substation serving secondarily to govern the operative connection of the signaling apparatus at the same substation with said lines, and means whereby an actuation of said first means due to the control exercised from the central station establishes a condition such that the substation control at the other substations of said first means is rendered ineffective, substantially as described.

75

80

5. In a selective party-line system, the combination with a central station, of lines running therefrom to a series of substations, signaling apparatus at each of said substations normally operatively disconnected from said lines, means primarily controlled from the central station whereby the signaling apparatus at any substation may be operatively connected with said lines and secondarily controlled from each substation, the control exercised from any one substation serving secondarily to govern the operative connection of the signaling apparatus at the same substation with said lines, and means whereby an actuation of said first means due to a control exercised either from the central station or any one substation establishes a condition such that the substation control at the other substations of the said first means is rendered ineffective, substantially as described.

7. In a selective party-line system, the combination with a central station, of lines running from the central station to a series of substations, one of said lines being normally broken at each substation, signaling apparatus at each substation normally disconnected from said broken line, means primarily controlled from the central station whereby any substation signaling apparatus may be connected with the broken line and secondarily controlled from each substation whereby the corresponding signaling apparatus may be connected with the broken line, and means automatically set in operation by an actuation of said first means

whereby the said broken line is built up, substantially as described.

8. In a selective party-line system, the combination with a central station, of lines running from the central station to a series of substations, one of said lines being normally broken at each substation, signaling apparatus at each substation normally disconnected from said broken line, means controlled from each substation whereby the corresponding signaling apparatus may be connected with said broken line, and means whereby an actuation of said first means controlled from any one substation establishes a condition such that the substation control at the other substations of the said first means is rendered ineffective, substantially as described.

9. In a selective party-line system, the combination with a central station, of lines running from the central station to a series of substations, one of said lines being normally broken at each substation, signaling apparatus at each substation normally disconnected from said broken line, means controlled from the central station whereby any of the signaling apparatus may be connected with said broken line, said means being secondarily controlled from each substation, whereby the corresponding signaling apparatus may be connected with said lines, and means whereby an actuation of said first means due to the control exercised from any one substation establishes a condition such that the substation control at the other substations of the said first means is rendered ineffective, substantially as described.

10. In a selective party-line system, the combination with a central station, of lines running from the central station to a series of substations, one of said lines being normally broken at each substation, signaling apparatus at each substation normally disconnected from said broken line, means primarily controlled from the central station whereby the signaling apparatus at any substation may be connected with the broken line, and secondarily controlled from each substation, whereby the corresponding signaling apparatus may be connected with said broken line, and means whereby an actuation of said first means due to a control exercised from the central station establishes a condition such that the substation control at the other substations of said first means is rendered ineffective, substantially as described.

11. In a selective party-line system, the combination with a central station, of lines running from the central station to a series of substations, one of said lines being normally broken at each substation, signaling apparatus at each substation normally disconnected from said broken line, means primarily controlled from the central station

whereby the signaling apparatus at any substation may be connected with the broken line, and secondarily controlled from each substation, whereby the corresponding signaling apparatus may be connected with said broken line, and means whereby an actuation of said first means due to a control exercised either from central or from any one substation establishes a condition such that the substation control at the other substations of the said first means is rendered ineffective, substantially as described.

12. In a selective party-line system, the combination with a central station, of lines running from the central station to a series of substations, one of said lines being normally broken at each substation, and means secondarily controlled from any one substation and primarily set in operation at the central station, adapted to build up said broken line automatically, substantially as described.

13. In a selective party-line system, the combination with a central station, of lines running from the central station to a series of substations, one of said lines being normally broken at each substation, and means primarily controlled from the central station and secondarily controlled from any substation, adapted to build up said broken line automatically, substantially as described.

14. In a selective party-line system, the combination with a central station, of lines running from the central station to a series of substations, one of the lines being normally broken at each substation, means controlled and set in operation at the central station adapted to build up said broken line automatically, and means for secondarily controlling said first means from each of said substations, substantially as described.

15. In a selective party-line system, the combination with a central station, of lines running therefrom to a series of substations, one of said lines being normally broken at each of said substations, a line-signal associated with the said lines at the central station, means located at each substation adapted to cause the actuation of said line-signal, and means set in operation by the actuation of said line-signal adapted to build up said broken line, substantially as described.

16. In a selective party-line system, the combination with a central station, of lines running therefrom to a series of substations, one of said lines being normally broken at each of said substations, a cord-circuit at the central station adapted for connection with said lines, a line-signal associated with the said lines at the central station, means located at each substation adapted to cause the actuation of said line-signal, means set in operation by the actuation of said line-signal adapted to build up said broken line, and means whereby the substation control of the

line-signal is rendered ineffective upon connection of said cord-circuit with said lines, substantially as described.

17. In a selective party-line system, the combination with the central station, of lines running therefrom to a series of substations, one of said lines being normally broken at each of said substations, a line-signal associated with the said lines at the central station, means located at each substation adapted to cause the actuation of said line-signal, and means set in operation by the actuation of said line-signal but primarily controlled from the said central station, whereby the broken line is automatically built up, substantially as described.

18. In a selective party-line system, the combination with a central station, of lines running therefrom to a series of substations, one of said lines being normally broken at each of said substations, a cord-circuit at the central station adapted for connection with said lines, a line-signal associated with the lines at the central station, means located at each substation adapted to cause the actuation of said line-signal, means set in operation by the actuation of said line-signal but primarily controlled from the said central station, whereby the broken line is automatically built up, and means whereby the substation control of the line-signal is rendered ineffective upon the connection of said cord-circuit with said lines, substantially as described.

19. In a selective party-line system, the combination with the central station of lines running therefrom to a series of substations, one of said lines being normally broken at each substation, a cord-circuit at the central station adapted for connection with said lines, a line-signal associated with the lines at the central station, means located at each substation adapted to cause the actuation of said line-signal, means set in operation by the actuation of said line-signal, but primarily controlled from said central station, whereby the broken line is automatically built up, and means whereby the substation control of said line-signal is rendered ineffective upon an actuation of the said line-signal caused from any one substation, substantially as described.

20. In combination, a source of electric current, a pole-changing switch associated therewith, an electromagnet adapted to actuate said pole-changing switch, switching means adapted to make connection with successive contacts, electromagnetic mechanism adapted to cause the step-by-step shifting of said switching means to successive contacts, and an electric circuit including the source of current, the switching means and the electromagnet adapted to actuate the pole-changing switch, said circuit being adapted to be completed through any predetermined contact, whereby the electromagnet will be energized to actuate the pole-changing switch upon a predetermined step of the switching means, substantially as described.

gized to actuate the pole-changing switch upon a predetermined step of the switching means, substantially as described.

21. In combination, a source of electric current, a pole-changing switch associated therewith, an electromagnet adapted to actuate said pole-changing switch, switching means adapted to make connection with successive contacts, electromagnetic mechanism adapted to cause a one-step shifting of said switching means to a successive contact upon a cessation of current-flow therethrough, a periodically-interrupted electric current flowing through said electromagnetic mechanism, whereby a step-by-step shifting of said switching means is caused, and an electric circuit including the source of current, the switching means and the electromagnet adapted to actuate the pole-changing switch, said circuit being adapted to be completed through any predetermined contact, whereby the electromagnet will be energized to actuate the pole-changing switch upon a predetermined step of the switching means, substantially as described.

22. In combination, a source of electric current, a pole-changing switch associated therewith, an electromagnet adapted to actuate said pole-changing switch, switching means adapted to make connection with successive contacts, an electromagnet adapted to cause the one-step shifting of said switching means to a successive contact upon a cessation of current-flow therethrough, means adapted to cause a periodically-interrupted current to flow through said electromagnet, and an electric circuit including the source of current, the switching means and the electromagnet adapted to actuate the pole-changing switch, said circuit being adapted to be completed through any predetermined contact, whereby the electromagnet will be energized to actuate the pole-changing switch upon a predetermined step of the switching means, substantially as described.

23. In combination, a source of electric current, a pole-changing switch associated therewith, an electromagnet adapted to actuate said pole-changing switch, switching means adapted to make connection with successive contacts, an electromagnet adapted to cause the one-step shifting of said switching means upon a cessation of current-flow therethrough, means controlled from the central station adapted to cause a periodically-interrupted current to flow through said electromagnet, and an electric circuit including the source of current, the switching means and the electromagnet adapted to actuate the pole-changing switch, said circuit being adapted to be completed through any predetermined contact, whereby the electromagnet will be energized to actuate the pole-changing switch upon a predetermined step of the switching means, substantially as described.

24. In combination, a source of electric current, a pole-changing switch associated therewith, an electromagnet adapted to actuate said pole-changing switch, switching means adapted to make connection with successive contacts, electromagnetic mechanism adapted to cause the step-by-step shifting of said switching means to successive contacts, an electric circuit including the source of current, the switching means and the electromagnet adapted to actuate the pole-changing switch, a selector-jack connected with each of said contacts, and a selector-plug adapted for insertion within any of said jacks, thereby completing said electric circuit through any predetermined contact, whereby the electromagnet will be energized to actuate the pole-changing switch upon a predetermined step of the switching means, substantially as described. 65
25. In combination, a source of electric current, a pole-changing switch associated therewith, an electromagnet adapted to actuate said pole-changing switch, switching means adapted to make connection with successive contacts, electromagnetic mechanism adapted to cause the step-by-step shifting of said switching means to successive contacts, an electric circuit including the source of current, the switching means and the electromagnet adapted to actuate the pole-changing switch, a selector-jack connected with each of said contacts, a selector-plug adapted for insertion within any of said jacks, thereby completing said electric circuit through any predetermined contact whereby the electromagnet will be energized to actuate the pole-changing switch upon a predetermined step of the switching means, and means whereby the insertion of the selector-plug within any selector-jack will cause the restoration of the switching means to its normal condition, substantially as described. 70
26. In combination, a source of electric current, a pole-changing switch associated therewith, an electromagnet adapted to actuate said pole-changing switch, switching means adapted to make connection with successive contacts, electromagnetic mechanism adapted to cause the step-by-step shifting of said switching means to successive contacts, an electric circuit including the source of current, the switching means and the electromagnet adapted to actuate the pole-changing switch, a selector-jack connected with each of said contacts, a selector-plug adapted for insertion within any of said jacks, thereby completing said electric circuit through any predetermined contact, whereby the electromagnet will be energized to actuate the pole-changing switch upon a predetermined step of the switching means, and means whereby the removal of the selector-plug from any selector-jack will cause the restoration of the switching means to its normal condition, substantially as described. 75
27. In combination, a source of electric current, a pole-changing switch associated therewith, an electromagnet adapted to actuate said pole-changing switch, switching means adapted to make connection with successive contacts, electromagnetic mechanism adapted to cause the step-by-step shifting of said switching means to successive contacts, an electric circuit including the source of current, the switching means and the electromagnet adapted to actuate the pole-changing switch, means adapted to close or break said circuit through any predetermined contact, and means whereby the actuation of said means to close said circuit causes a restoration of said switching means to its normal condition, substantially as described. 80
28. In combination, a source of electric current, a pole-changing switch associated therewith, an electromagnet adapted to actuate said pole-changing switch, switching means adapted to make connection with successive contacts, electromagnetic mechanism adapted to cause the step-by-step shifting of said switching means to successive contacts, an electric circuit including the source of current, the switching means and the electromagnet adapted to actuate the pole-changing switch, means adapted to close or break said circuit through any predetermined contact, and means whereby the actuation of said means to break said circuit causes a restoration of said switching means to its normal condition, substantially as described. 85
29. In combination, a source of electric current, a pole-changing switch associated therewith, an electromagnet adapted to actuate said pole-changing switch, switching means adapted to make connection with successive contacts, electromagnetic mechanism adapted to cause the step-by-step shifting of said switching means to successive contacts, an electric circuit including the source of current, the switching means and the electromagnet adapted to actuate the pole-changing switch, a selector-jack connected with each of said contacts, a selector-plug adapted for insertion within any of said jacks, thereby completing said electric circuit through any predetermined contact, whereby the electromagnet will be energized to actuate the pole-changing switch upon a predetermined step of the switching means, and an auxiliary contact in each of said selector-jacks adapted to make momentary contact with said selector-plug upon insertion in or removal from said jack, said contact being adapted to close an electric circuit through electromagnetic mechanism adapted to cause the restoration of said switching means to its normal condition, substantially as described. 90
30. In combination, a source of electric cur-

- rents, two circuits electrically connected therewith, means for causing the current-flow from said source to be intermittent, means for reversing the connection of the first of said circuits with said source of currents, and means adapted to disconnect the second circuit from said source during the reversal of the connection of said first circuit, substantially as described.
31. In combination, a source of electric currents, two circuits electrically connected therewith, means for causing the current-flow from said source to be intermittent, a pole-changing switch for reversing the connection of the first of said circuits with said source of currents, and means adapted to disconnect the second circuit from said source during reversal of the connection of said first circuit, substantially as described.
32. In a selective party-line system, the combination with a central station of three lines running therefrom to a series of substations, signaling apparatus at each of said substations normally operatively disconnected from said lines, means at each substation absolutely controlled from the central station and secondarily controlled from the said substation, whereby the corresponding signaling apparatus may be connected with two of said lines, and means whereby an actuation of said first means controlled from the corresponding substation, establishes a condition such that the substation control of the said first means is rendered ineffective, substantially as described.
33. In a selective party-line system, the combination with a central station of three lines running therefrom to a series of substations, signaling apparatus at each of said substations, normally operatively disconnected from said lines, means at each substation directly controlled from the said substation, whereby the corresponding signaling apparatus may be connected with two of said lines, and means whereby an actuation of said first means controlled from any substation, establishes a condition such that the substation control of the said first means is rendered ineffective, substantially as described.
34. In a selective party-line system, the combination with a central station of lines running from the central station to a series of substations, one of said lines being normally broken at each substation, signaling apparatus at each substation normally disconnected from said broken line, means controlled from each substation, whereby the corresponding signaling apparatus may be connected with the broken line, and means automatically set in operation by an actuation of said first means, whereby the said broken line is built up, substantially as described.
35. In a selective party-line system, the combination with a central station of lines running from the central station to a series of substations, one of said lines being normally broken at each substation, and means controlled from any one substation and set in operation at the central station, adapted automatically to build up a non-inductive circuit through said broken line, substantially as described.
36. In a selective party-line system, the combination with a central station of lines running from the central station to a series of substations, one of said lines being normally broken at each substation, and means primarily controlled from the central station, and secondarily controlled from any substation, adapted automatically to build up a non-inductive circuit through said broken line, substantially as described.
37. In a selective party-line system, the combination with a central station of lines running from the central station to a series of substations, one of said lines being normally broken at each substation, means controlled and set in operation at the central station, adapted automatically to build up a non-inductive circuit through said broken line and means for secondarily controlling said first means from each of said substations, substantially as described.
38. In a selective signaling party-line system, the combination with a central station of lines running therefrom to a series of substations, one of said lines being normally broken at each substation, a cord-circuit at the central station adapted for connection with said lines, a line-signal associated with said lines at the central station, means located at each substation, adapted to cause the actuation of said line-signal, and means whereby the substation control of the line-signal is rendered ineffective upon the connection of said cord-circuit with said lines, substantially as described.
39. In a selective party-line system, the combination with a central station, of lines running therefrom to a series of substations, one of said lines being normally broken at each substation, a cord-circuit at the central station adapted for connection with said lines, a line-signal associated with the lines at the central station, means located at each substation, adapted to cause the actuation of said line-signal, whereby the broken line is automatically built up, and whereby the substation control of said line-signal is rendered ineffective upon an actuation of the line-signal, caused by the control exercised from any one substation, substantially as described.
40. In combination a source of electric current, current-reversing means associated therewith, an electromagnet adapted to actuate said current-reversing means, switching means adapted to make connection with successive contacts, electromagnetic mechanism adapted to cause the step-by-step shifting of said switching means to successive

contacts and an electric circuit including the source of current, the switching means and the electromagnet adapted to actuate the current-reversing means, said circuit being adapted to be completed through any predetermined contact whereby the electromagnet will be energized to actuate the current-reversing means upon a predetermined step of the switching means, substantially as described.

41. In combination, a source of electric current, current-reversing means associated therewith, an electromagnet adapted to actuate said current-reversing means, switching means adapted to make connection with successive contacts, electromagnetic mechanism adapted to cause a one-step shifting of said switching means to successive contacts upon a cessation of current-flow therethrough, a periodically - interrupted electric current flowing through said electromagnetic mechanism, whereby a step-by-step shifting of said switching means is caused, and an electric circuit including the source of current, the switching means and the electromagnet adapted to actuate the current-reversing means, said circuit being adapted to be completed through any predetermined contact whereby the electromagnet will be energized to actuate the current-reversing means upon a predetermined step of the switching means, substantially as described.

42. In combination, a source of electric current, current-reversing means associated therewith, an electromagnet adapted to actuate said current-reversing means, switching means adapted to make connection with successive contacts, electromagnetic mechanism adapted to cause the step-by-step shifting of said switching means to successive contacts, an electric circuit including the source of current, the switching means and the electromagnet adapted to actuate the current-reversing means, means adapted to close or break said circuit through any predetermined contact, and means whereby the actuation of said means to close said circuit, causes a restoration of said switching means

to its normal condition, substantially as described.

43. In combination, a source of electric current, current-reversing means associated therewith, an electromagnet adapted to actuate said current-reversing means, switching means adapted to make connection with successive contacts, electromagnetic mechanism adapted to cause the step-by-step shifting of said switching means to successive contacts, an electric circuit including the source of current, the switching means and the electromagnet adapted to actuate the current-reversing means, means adapted to close or break said circuit through any predetermined contact, and means whereby the actuation of said means to break said circuit, causes a restoration of said switching means to its normal condition, substantially as described.

44. In combination, a source of electric current, current-reversing means associated therewith, an electromagnet adapted to actuate said current-reversing means, switching means adapted to make connection with successive contacts, electromagnetic mechanism adapted to cause the step-by-step shifting of said switching means to successive contacts, an electric circuit including the source of current, the switching means and the electromagnet adapted to actuate the current-reversing means, a selector-jack connected with each of said contacts, a selector-plug adapted for insertion within any of said jacks, thereby completing said electric circuit through any predetermined contact whereby the electromagnet will be energized to actuate the current-reversing means upon the predetermined step of the switching means, substantially as described.

In witness whereof we hereunto subscribe our names this 6th day of October, A. D. 1902.
